UNITED STATES PATENT OFFICE

LOUIS T. MATHEWS, OF HOUSTON, TEXAS

COPYHOLDER ATTACHMENT FOR TYPEWRITERS

Application filed January 11, 1927, Serial No. 160,349. Renewed July 11, 1930.

My invention relates to copyholders to be employed with typewriters and other similar typing machines wherein the copy is held for the convenience of the typist, and means are provided for marking the position of the typist in copying from the notes. This invention is an improvement upon the construction disclosed in my prior Patent No. 1,587,342, issued June 1st, 1926.

10 An object of the invention is to provide a position indicator for use with a copyholder which will be convenient to attach to and be operated by the typewriter. It is desired that the copyholder be provided with 15 markers to indicate the position of the pointer as to the line of the copy which is being operated upon and the position of the pointer on said line.

It is an object to provide an automatic 20 means for adjusting the marker through the operation of the typewriter itself.

It is a further object to provide a marker so constructed as to engage and operate upon sheets of copy of any desired width.

25 The invention further resides in means upon the typewriter for adjustably engaging the indicator controlling means. It is also desired to construct an indicator which is adjustable upon the connecting line. Other 30 objects and advantages reside in the particular construction and arrangement of the parts and will be set out with detail in the specification which follows.

Referring to the drawing herewith, Fig. 1 35 is a front elevation of a copyholder embodying my invention. Fig. 2 is a rear elevation, certain parts being broken away. Fig. 3 is a broken detail of the graduated scale indicating the position of the pointer on the line 40 which is being copied. Fig. 4 is a detail of the lever controlling the adjustment of the copyholder. Fig. 5 is a vertical section through the operating lever and the parts operated thereby. Fig. 6 is a side elevation 45 of the operating lever and its connected parts.

Fig. 7 is a side elevation of the copyholder. Fig. 8 is a top plan view of the indicator. Fig. 9 is a front elevation thereof. Fig. 10 is an edge view of said indicator. Fig. 11 is a broken elevation of a portion of the typewriter with my line clamping means thereon; and Fig. 12 is a side elevation of the parts shown in Fig. 11. Like numerals of reference are employed to indicate like parts in all the views.

The general construction of my copyholder is quite similar to the structure disclosed in my prior patent, above referred to. The holder comprises an upright frame comprising a base member 1, a rear plate 2 secured thereto and extending upwardly to the desired height, the said rear plate having two forwardly extending flanges 3 thereon.

Secured to the plate 2 is an adjustable holder plate 4, the forward face of which is a plane and having rearwardly extending flanges 5 thereon to fit about the flanges 3 upon the rear plate upon which the holder plate is adapted to slide. The said flanges 5 are curved inwardly at the rearward side to engage about the supporting rear plate 2.

The holder plate 4 is adjustable upon the rear plate by means of a flexible cord, indicated at 6. Said cord is secured to the holder plate adjacent the lower end thereof at each side and extends upwardly over the rollers 7 and 8 and thence downwardly between the plates 2 and 4 about a pulley 9, thence laterally around a pulley 10 and forwardly to be wound about a spool 11 to which the line 80 is secured by a screw 12, or other similar means. It will be noted that when the flexible line 6 is wound about the spool 11 it will serve to elevate the holder in an obvious manner.

The means by which the holder plate 4 is operated through the spool 10 can best be understood from Figs. 4, 5 and 6. The spool 11 is mounted upon a shaft 13 which extends through the side walls of a narrow sheet metal 90

housing 14. The spool comprises a short drum mounted on said shaft and having at one end thereof a radially extending ratchet wheel 15. The teeth on said ratchet are adapted to be engaged on their rearward sides by a pawl 15^a normally held by a spring 16 into engagement with the teeth of said ratchet wheel.

Mounted above the pawl 15^a is a second hand-operated pawl 17, said pawl having an upwardly extending arm 18 thereon, said arm having a handle 19 extending forwardly into position for operation by the typist. The arm 18 is pivoted at 20 to a bracket 21 upon a hand-operated lever 22.

The lever 22 is pivoted at its forward end 23 upon a pin mounted in the housing. The arm of lever 22 extends upwardly within the housing and through an opening 23 therein and is then extended forwardly and provided with a handle 24 adjacent the operator. The lever arm 22 is held normally in raised position by means of a spring 25, one end of which is attached to the housing and the other end to the forward portion of the lever. It will be noted that the forward movement of the said lever is limited by an adjustable set screw 26 secured through the top wall of the casing immediately above said lever. The lever 18 extends through an opening 27 in the lever 22 and is held normally in raised position by a spring 28 secured to the lever arm 22.

It will be noted, therefore, that when the arm 22 is pushed downwardly by the operator it will rotate the spool 11 to wind the flexible line 6 thereon. When it is desired to release the line 6 to allow the holder to drop, the lever 19 is also depressed, forcing the pawl 17 out of contact with the ratchet and against the pawl 15^a in such manner as to disengage the pawl 15^a and allow the line to be unreeled. A spring 30 secured to the lower wall of the housing and bearing against the ratchet wheel 15 tends to prevent too rapid rotation of the wheel under the weight of the holder. Two shock absorbing springs 31 are mounted on the base immediately below the holder to receive the shock of the holder when it is dropped, and further to prevent jar upon the apparatus.

The present invention includes an automatic means for moving the copyholder through the operation of the typewriter. In performing this function, the carriage of the typewriter is adapted to engage an upwardly extending arm 32, shown best in Figs. 1 and 6. Said arm 32 is provided with openings 33 therein for connection by a thumb screw 34 to a lever arm 32', the lower end of which is mounted upon a supporting axis 35. The joint in the arm 32 thus provided allows the upper portion of the operating arm to be thrown laterally out of the way of the car-

riage of the typewriter when the automatic operation is dispensed with.

The axis or shaft 35 is mounted at its ends in brackets 36 secured to the side wall of the housing so as to allow rotative movement of the axis in said brackets. Secured upon the shaft 35 is a laterally extending arm 37 extending to a point directly over the operating lever 22 and adapted to engage said lever when said shaft 35 is rotated by the carriage of the typewriter. A spring 38 upon the shaft 35 tends to hold the arm 37 upwardly out of engagement with the arm 22. A stop member 39 extending into the path of said arm 37 limits its movement upwardly.

In the use of this automatic adjusting means, the typewriter carriage will engage with the arm 32 adjacent the end of its movement in typing and will move said arm to the right of its position in Fig. 1. This will rotate the shaft 35 and force the arm 37 against the operating arm 22 and depress said arm so as to rotate the spool and move the copyholder, as previously described. It is to be understood that the depression of the lever 22 in this manner will be sufficient to elevate the holder 4 one space upon the copy.

The holder plate 4 is provided, adjacent the left-hand edge thereof, with a graduated scale 40, the marks thereon being spaced the proper distance apart to mark the usual distance between lines typed by the typewriter. The holder will, therefore, move through the adjustment of the operating means one or some multiple of these spaces at each movement of the operating lever 22.

The paper or manuscript constituting the copy which is being typed will be held upon the holder plate 4 by clamping means so arranged as to allow the use of sheets of any ordinary width, thus making it unnecessary to provide different widths of holders. This clamping means includes as its principal member a frame made up of a U-shaped rod 41 having two side arms extending vertically upward at each side of the holding plate 4, as shown in Fig. 1. The lower ends of these two rods are connected by a cross member 42, shown in Fig. 2. This cross member is mounted to rock in brackets 43 at each side of the frame. Between the arms the cross member is curved upwardly to provide a crank arm at the rear of the frame. To the upwardly extending crank arm 42 of the cross member I attach tension springs 43', secured to brackets 44 at the lower end of the frame and extending rearwardly therefrom to exert a pull outwardly and downwardly, as shown in Fig. 7. The pull exerted by the springs 43' tends to hold the upper ends of the rods rearwardly or toward the holding plate 4, as will be easily understood from Fig. 7.

The upper ends of the rods are attached to the ends of the marker 45, which is held

by the said arms against the forward face of the holding plate 4. Said marker is a straight edge rule having a scale 46 thereon with degrees marked thereon the usual distance apart of the letters in the type-written matter. This marker is made up of a piece of sheet metal secured to the upper ends of said rods 41 and having an upper edge 47 bent rearwardly to bear against the face of the holder, as shown in Fig. 7. The body of the plate is recurved upwardly at the lower end, the recurved portion being spaced from the body to include a pulley 48 at each end of the said marker within which a flexible line 49 may pass. Said line 49 extends downwardly at each end about a pulley 50 at one side of the holder and a drum 51 at the opposite side of the holder, said drum being supported upon a frame comprising brackets 52 mounted upon the rods 41 at each side of the holder, said brackets including a forwardly extending arm 53 thereon, at the outer end of which is a spacing rod 54, each end of which is recurved to include a pin 55, upon which the pulley or drum is rotatable. The drum 51 has a series of spools of different sizes thereon and about which the line 49 may pass, it being understood that the adjustment of the line upon the different spools of said drum will control the space to which the line is moved by the typewriter.

The line 49 has a pointer or indicator 56, the construction of which is shown in Figs. 8, 9 and 10. It comprises a plate or strip of metal, the upper end 56 of which is pointed and curved rearwardly to lie against the edge of the marker 45. The lower end of the strip is curved upwardly in front of the body of the marker to a point adjacent the upturned edge of the marker 45 and is then curved forwardly and downwardly to lie against the scale 40 upon the marker. This forwardly directed member 58 moves with the line to indicate that point upon the typewriter, shown by the pointer on the ordinary typewriter scale, which is usually found upon typewriters. It is understood, therefore, that the scale 40 on the marker is a duplicate of the scale ordinarily found upon a typewriter and that the marking pointer 58 is moved simultaneously with the marker on the typewriter scale.

The marker has two laterally extending arms 59, the ends 60 of which are forked and bent forwardly at an inclination, as shown in Fig. 8. A U-shaped spring member 61 has its lower end within the recurved portion of the marker and its arms extend upwardly within the inturned fingers 60 of the arms 59. This spring member 61 is curved forwardly at 62 at the upper ends to provide handles which may be engaged by the operator and pressed inwardly toward the marker. The flexible line 49, which extends

between the drums 50 and 51, passes through said pointer between the arms of the spring member 61 and the arms 59. To engage this marker at its desired position upon the line 49, the ends 2 of the spring are pressed inwardly so as to loosen their hold upon the line 49. The pointer may then be adjusted laterally along the line to any desired point. The handle 62 may then be released and the resiliency of the spring will force the arms of the spring member 61 into the space behind the fingers 60 and thus tend to clamp the line 49 between the spring member 61 and the arms 59, as will be understood from Figs. 8 and 9.

Upon the usual typewriter there is upon the carriage of the typewriter, above the cylindrical plate 64, a curved plate 65 of sheet metal, which is sometimes called the paper table. I contemplate securing to this curved member 65 of the typewriter two spaced spring arms 66, the lower ends of which are extended laterally at an angle to the body of the spring and secured on opposite sides of the typewriter table 65. These two spring arms are thus spaced apart by the thickness of the table 65, as shown in Fig. 12. The arms 66 are curved rearwardly away from the typewriter toward the copy and have slidably thereon a collar 67. Said collar fits tightly over said arms and tends to compress them toward each other. Thus, when the line 49 is engaged between the arms 66, as shown in Fig. 12, the sleeve 67 may be moved toward the point where the line 49 is engaged and will clamp the arms together, thus clamping the line securely to the typewriter carriage. This position of the clamping member is indicated in Fig. 1, the plate 65 being shown in dotted lines.

The copy is held to the face of the holder largely by means of the marker 45. There are also at the upper end of the holder plate 4 additional clamping arms 68, which are preferably formed upon the ends of a rod 69. Said rod extends across the rearward side of the plate 4 and has a downwardly curved central portion 70, to which is secured a tension spring 71, which, as shown in Fig. 7, tends to throw the outer ends of said rod forwardly against the face of the holder. Said rod is journaled in brackets 72 at the side of the frame and the ends are curved upwardly and forwardly and the ends then bent laterally parallel with the face of the plate, the lateral arms 73 thus provided, being adapted to lie against the face of the copy and hold it against the plate 4. It will be observed that the copy lying against the face of the plate may be of any desired width, as the edges of said copy sheet may extend laterally beneath the arms 68.

I have also provided an arm 75, shown in my prior patent above referred to, said arm lying upon the top of the plate, as shown in Fig. 1, and acting to hold the copy in posi-

70

130

tion relative to the plate when it is extended over the top of the holder plate.

In case an unusually wide sheet of copy is being handled, I support the same at each side of the holder plate 4 by means of arms 76. Said arms are made up of the straight rods extending through openings 77 in the sides of the frame and through brackets 78 mounted at the upper edge of the frame on the rearward side thereof. A cotter pin or other similar means 79 may extend through the inner ends of said rods and limit their movement outwardly. When not in use, they may be moved inwardly, sliding within the frame in an obvious manner to a position out of the way. As a provision for further usefulness of the holder, I may place a mirror, indicated at 80, within the plate 4 at a central point, said mirror adding to the general appearance 20 of the holder and serving a useful purpose when the copy is removed.

The operation of this device will be clear from the description already given. The copyholder will be placed in proper spaced relation relative to the typewriter practically immediately behind the machine. The line 49 operating the indicator will be then clamped between the two spring members 66 on the typewriter carriage, so that the movement of the carriage will move the line simultaneously and to the same degree as the carriage is moved. The movement of the carriage will move the pointer along the scale 46 to the same degree that the pointer upon the typewriter is moved, so that the typist may set the pointer both on the typewriter and the indicator at the same point on the scale to indicate where the line begins upon the copy being made. As the typewriter carriage approaches the end of the line which is typed, it will engage the arm 32 of the marker operating mechanism and will force the arm 22 downwardly to rotate the ratchet wheel 15 and the spool 11, so as to wind up the flexible cord 6 and elevate the copyholder, the movement of the lever being sufficient to elevate the copyholder the equivalent of one space on the copy.

It is believed that the improvements herein made upon the copyholder shown in my prior patent will be obvious without further description.

What I claim as new and desire to protect by Letters Patent is:

1. In a typewriter copyholder, a base, an upright frame thereon, a copyholding plate slideable on said frame, a line marker adjacent the upper end of said frame and means to hold said marker resiliently against said plate comprising a U-shaped rod, the arms of which extend upwardly at each side and in front of said plate, the lower end of said rod being adjacent said base and curved to extend behind said plate, supporting brackets for said rod and springs acting to hold said arms toward said plate.
2. In combination, a typewriter including

a movable carriage, a copyholder vertically adjustable relative to said typewriter, a hand lever adjacent said typewriter operatively connected with said copyholder to move the same, a carriage-engaging lever extending above said hand lever, an arm on said carriage-engaging lever adapted to contact with said hand lever and to depress the same when said carriage engages said carriage-engaging lever.

3. In combination, a typewriter including a movable carriage, a copyholder vertically adjustable relative to said typewriter, a hand lever adjacent said typewriter operatively connected with said copyholder to move the same, a rotatable shaft adjacent said hand lever, a carriage-engaging lever extending above said hand lever and fixed to said shaft, an arm on said carriage-engaging lever adapted to contact with said hand lever and to depress the same when said carriage engages said carriage-engaging lever.

4. In combination, a typewriter including a movable carriage, a copyholder vertically adjustable relative to said typewriter, a hand lever adjacent said typewriter operatively connected with said copyholder to move the same, a carriage-engaging lever extending above said hand lever, an arm on said carriage-engaging lever adapted to contact with said hand lever and to depress the same when said carriage engages said carriage-engaging lever, and means to normally hold said arm out of contact with said hand lever.

5. In combination, a typewriter including a movable carriage, a copyholder vertically adjustable relative to said typewriter, a hand lever adjacent said typewriter operatively connected with said copyholder to move the same, a carriage-engaging lever extending above said hand lever, and an arm on said carriage-engaging lever adapted to contact with said hand lever and to depress the same when said carriage engages said carriage-engaging lever, said carriage-engaging lever being jointed to fold out of the path of said carriage.

6. A copyholder, including a base, an upright frame thereon, a copyholding plate slideable on said frame, a line marker adjacent the upper end of said frame and means to hold said marker resiliently against said plate comprising a U-shaped rod, the arms of which extend upwardly at each side and in front of said plate, the lower end of said rod being adjacent said base and curved to extend behind said plate, supporting brackets for said rod and springs acting to hold said arms toward said plate.

7. A copyholder, including a base, an upright frame thereon, a copyholding plate slideable on said frame, a line marker, and means to hold said marker resiliently against said plate comprising a U-shaped rod, the arms of which extend upwardly at each side

and in front of said plate, the lower end of said rod being adjacent said base and curved to extend behind said plate, supporting brackets for said rod, a crank arm on said rod behind said plate, and means on said crank arm acting to hold said arms toward said plate.

8. In a copyholder, a base, a frame thereon, a holder plate slidable on said frame, a line marker, supporting arms for said marker secured to each end thereof, said arms being spaced slightly in front of said plate to include any desired width of paper, and means on said base connected with said arms and holding said marker against said plate.

10. In a copyholder, a base, a frame thereon, a holder plate slidable on said frame, a line marker, supporting arms for said marker secured to each end thereof, said arms being spaced slightly in front of said plate to include any desired width of paper, and means on said base connected with said arms and holding said marker against said plate.

20. In a copyholder including a holder plate, a line marker thereon and a flexible line movable along said marker, the combination of an indicator on said line comprising a strip of metal with its upper end pointed to project above said marker, its lower end being recurved in front of said line, and having its tip bent downwardly in front of said marker, a pair of inclined guide fingers at each side of said metal strip, and a U-shaped spring fitting resiliently under said guide fingers 35 and adapted to clamp said line against said strip.

11. In a copyholder including a holder plate, a line marker thereon and a flexible line movable along said marker, the combination 40 of an indicator on said line comprising a metal strip having its ends formed into pointers, one directed upwardly along said marker and the other downwardly, a pair of inclined guide fingers at each side of said metal strip, and a U-shaped spring fitting resiliently under said guide fingers and adapted to clamp said line against said strip.

12. In a copyholder including a holder plate, a line marker thereon, said marker having a graduated scale thereon and a flexible line movable along said marker, the combination 50 of an indicator on said line comprising a metal strip having its ends formed into pointers, one directed upwardly along said marker and the other downwardly to bear upon said scale, a pair of inclined guide fingers at each side of said metal strip, and a U-shaped spring fitting resiliently under 55 said guide fingers and adapted to clamp said line against said strip.

13. In a typewriter including a movable carriage, a sheet metal plate thereon, a pair of resilient arms secured to said plate on opposite sides thereof and curved rearwardly 65 of said carriage, and a collar fitting slidably

on said arms and tending to force said arms toward each other to act as a line gripping means.

14. A copyholder including a base, an upright frame, a copyholding plate slidable thereon, arms pivoted at their lower ends on said frame adjacent said base, and extending upwardly in front of said plate, and a marker at the upper ends of said arms.

In testimony whereof I hereunto affix my 75 signature this 6th day of January, A. D. 1927.

LOUIS T. MATHEWS.
